UNITED STATES PATENT OFFICE.

MARCUS B. BEHRMAN, OF NEW YORK, N. Y., ASSIGNOR TO THE LOX SEAL CORPORATION, OF NEW YORK, N. Y., A CORPORATION OF NEW YORK.

PACKAGING.

Application filed July 6, 1925. Serial No. 41,512.

My present invention relates generally to improvements in packaging and involves the method and means for securing portions of a package or container against separation.

5 Merchants who give credit or permit the return of merchandise find that they serve losses by the surreptitious removal of merchandise from the container. Furthermore, it is a common practice for a prospective customer to order up merchandise and after making use of or otherwise handling the contents to then return the merchandise for credit or exchange, and my invention has particular utility to prevent such practices occurring without detection. Its utility, however, extends generally to the field of packages and containers and of maintaining the package or containers or the container closures in predetermined condition or position, and certain phases of my invention may serve even a broader field of utility.

One of the objects of my invention is the provision of an arrangement whereby a container closure can be associated with the container against accidental removal therefrom and then affixed thereto so that the closure member cannot be removed without detection.

A further object of my invention is the provision of a simple and inexpensive means which on the one hand permits of rapidly fastening receptacles, containers or the like, and on the other hand insures against opening of the receptacle or tampering with the contents thereof, and which therefore provides a means for detecting the breach of a specific provision against such acts imposed by the merchant.

Containers of the type in which the box elements are in the form of sheets, which are folded to form the box parts are generally provided with means for maintaining the box parts in their shaped or folded condition. Another object of my invention is the provision of an arrangement for maintaining a box part in its shaped or folded condition and more particularly, the provision and arrangement for such purpose of fastening elements which not only maintain such box part in such condition, but also serve to hold the box parts together so as to maintain the receptacle or container in a closed condition

and more particularly the arrangement in the elements of which the parts are formed whereby the fastening elements can be associated therewith for such purposes.

A still further object of my invention is the provision of fastening elements of such a character that they coact with the box parts not only to maintain such box parts associated together and where the box parts are either or each in the form of a sheet or blank to be folded to form the box part, to maintain such part in its folded condition but also permit of their being sealed together so as to prevent any separation of the parts without detection.

A still further object of my invention is the provision of fastening elements which not only serve the functions set forth, but also serve to brace the box against undue distortion and are so positioned and associated as to brace the box structure.

For the attainment of these objects and such other objects as may hereinafter appear or be pointed out, I have illustrated embodiments of my invention in the accompanying drawings, wherein

Fig. 1 is a perspective view of one embodiment of my invention;

Fig. 2 is a section taken on line 2—2 of Fig. 1 through the securing means;

Fig. 3 is a top elevational view of one of the locking elements of Fig. 2;

Fig. 4 is a sectional view similar to that of Fig. 2, showing the employment of a modified securing means;

Fig. 5 is an exploded view of the fastening means employed in the embodiment of Fig. 4;

Fig. 6 is a perspective view of the lower end of the box of Fig. 1 with the box turned upside down showing the fastening means employed at the bottom;

Fig. 7 is a section taken on line 7—7 of Fig. 6;

Fig. 8 is an elevational view of one of the locking elements of Fig. 7;

Fig. 9 is a section similar to Fig. 7 showing the employment of a modified form of securing means;

Fig. 10 is an exploded view of the securing means of Fig. 9;

Fig. 11 is an exploded view of a modified

form of container employing a still further embodiment of my securing means;

Fig. 12 is a perspective view of the box parts of Fig. 11 secured together in partially locked association;

Fig. 13 is a section taken on line 13—13 of Fig. 12;

Fig. 14 shows one of the fastening elements of Fig. 12;

10 Fig. 15 is an exploded view of a modified embodiment of the securing means.

Upon viewing Figs. 1 and 6 of the drawing, it will be observed that I have here illustrated my invention as embodied in a box 15 construction which comprises the box body 10, the insertable top closure member 11 and the insertable bottom closure member 12 (see Fig. 6).

As will be understood, in this type of box 20 both the top and the bottom closure members 11 and 12 are provided with the continuous upstanding flanges 13 and 14 respectively, which are adapted and arranged to be received and to fit snugly in the opposite 25 open ends of the box body 10 so as to have the upper and lower edges of the walls 13 and 14 of the top and bottom closures flush with the top and bottom edges of the body member 10 respectively, all as shown 30 in the drawing.

The box body 10 is provided at its upper edge with any preferred or desired number of horizontally elongated slots or perforations 16 and the top closure member 11 is 35 similarly provided with a corresponding number of horizontally elongated openings or slots 17 preferably arranged so as to have the two groups of slots brought into registration when the top closure member 11 40 is positioned as shown in Fig. 1, the two groups of slots being preferably of the same dimensions for obvious reasons.

To hold the top closure member 11 in its position of association with the box body, 45 I provide the securing means shown more in detail in Figs. 2 and 3 of the drawing; these fastening means comprising preferably two separate elements or members, to one of which I have applied the reference character 50 20 and the other 21.

The fastening element 20 shown more in detail on the right in Fig. 5 is preferably in the form of a metal stamping made from a single piece of material and bent intermediate its ends to form the nose 22, the two legs 23 and 24 first gradually diverging as shown in Fig. 5 and then rapidly converging to bring the two into contacting relation as shown at 26 and 27 to form the 55 neck portion, the two superposed elements of this neck portion being cut away at their top and bottom as shown at 28 and 29, the terminal portions of the fastener being turned at right angles thereto to form the 60 feet 30 and 31, all as shown in section in 65

Fig. 2 and in perspective on the right of Fig. 5 of the drawings. The diverging legs 23 and 24 are provided with the openings 32 and 33 therethrough, preferably in registry with each other. The other securing element or fastener 21 is shown in detail in Fig. 3 and preferably comprises a sheet of hardened spring metal slotted parallelly and transversely as shown at 35 and 36 and also longitudinally by a connecting slit so as to 70 provide the two spring lips 37 and 38 which are preferably forced outwardly and upwardly all for purposes that will be understood shortly. It will be observed upon viewing Fig. 3 that the slits 35 and 36 are 75 positioned intermediate the upper and lower edges and terminate short of the side edges and that the cut connecting the two terminates substantially intermediate the ends of the cuts 35 and 36.

It will be understood that the registering horizontal slots 16 and 17 adjacent the top of the box body 10 and formed in the side wall 13 of the top closure 11 are of a horizontal length slightly greater than the width of the legs 23 and 24 of the fastener 20 and are of a width slightly less than the distance between the outer side surfaces of the legs 23 and 24 at their widest portion, so that while the fastener 20 when positioned horizontally can be passed through the registering slots 16 and 17, to do so will require a slight compression and distortion of the two leg members 23 and 24, and the dimensions of the parts are such that when a fastener 20 has been passed through two registering orifices or slots 16 and 17, with the feet 30 and 31 in abutting relation to the inner surface of the upstanding wall 13 of the top closure member, the leg portions 23 and 24 100 will have passed fully beyond the superposed box layer materials; and upon the diverging legs 23 and 24 assuming their normal position, the shoulders 40 and 41 thereof formed by the rapid convergence of the two leg members 23 and 24 may be positioned in abutting relation to the outside surface of the box member 10 and adjacent the edges of the slot so that the fastening element 20 will be held in this position against 105 accidental removal which will be its preliminary position of association, it being understood that the box parts will not be drawn tightly toward each other.

In the preferred practice of my invention, 110 the length of the narrow parts 28 and 29 of the neck correspond to the thickness of the layers of material formed at the top by the overlapping of the wall 13 of the top closure 11 and the body member 10, so that the 115 widened part 26 and 27 of the neck portion will also extend beyond the outer surface of the box body 10, and in this position the fastening elements 20 can be turned through an angle of 90° so as to cause the shoulders 120

115

120

125

130

formed between the neck portions 26, 27, 28 and 29 to be in abutting relation to the outer surface of the box body 10 so that the fastener will be held in this position with the 5 double layer of material comprising the box body 10 and the wall 13 of the top closure member 11 received between the feet 30 and 31 and the aforementioned shoulders joining the narrow portions 28 and 29 and the 10 widened portions 26 and 27 of the neck portion of the fastener.

In order to lock the headed fastener 20 in this position and absolutely prevent its removal without detection, I employ the locking means shown in Fig. 3 of the drawing, 15 as follows:—

The opening 45 formed between the two upwardly curved lips 37 and 38 is brought 20 into registry with the nose 22 of the fastener 20 and is forced thereover, the diverging faces of the legs 23 and 24 forcing these lips upwardly and outwardly until these lips pass the shoulders 40 and 41 upon which the 25 spring lips 37 and 38 will resume their normal position in back of these shoulders and thus not only lock the fastener 34 (see Fig. 3) closely adjacent the box but also absolutely prevent the removal of the fastening element 20.

30 The locking lips 37 and 38 which serve to lock the fastener parts or members against separation and removal, are exposed, and for this reason always present the possibility that by compressing or otherwise manipulating either the lips or the shoulders 40 and 41, a person may succeed in removing the locking member 34 and to prevent this, I show the modified embodiment of Figs. 4 and 5 in which I employ a modified form of 35 fastener 34' made of material similar to the fastener 34 of Fig. 3, and provided with the transverse parallel cuts 35' and 36' and the bent up lips 37' and 38', and in addition provide this locking element 34' with a cover member 45' preferably integral therewith and which is imperforate except that it is provided with a central slot or opening 46' just of a size to permit the legs 23 and 24 of the fastening member to pass there- 40 through and covers the full face of the locking member 34', and in Fig. 4 of the drawing, I show these two members 20 and 34' assembled with the box elements 10 and 13, and as will be observed, the cover member 45' will absolutely prevent any manipulation of the lips 37' and 38', and thus prevent any possibility of separating the elements 20 and 21'.

In a structure of this character, it is frequently desirable that a string be passed 60 about the box for a number of reasons and to permit of this, in connection with my fastener, I have provided the legs 23 and 24 with the orifices 32 and 33 as already

described, and when the elements 20 and 21 or 21' have been assembled and associated together with the box parts as shown in Figs. 1, 2 and 4 of the drawing, the legs 23 and 24 present these openings 32 and 33 in horizontal registry so that a string 48 can be passed therethrough and about the box and the ends of the string secured together in any preferred or desired manner, as by having it associated with a locking seal 49 as shown in the drawing.

Upon viewing Fig. 6 of the drawing, it will be here observed that I show the employment of a modified form of fastener for securing the bottom body closure 12 in position, although as will be understood, all the forms of the fastener are interchangeable. One of the types of fastener which I here employ is shown in section in Fig. 7 of the drawing and comprises the members 50 and 51, the member 50 being preferably 80 in the form of a tubular member 52 closed at its outer end 53 and provided with the outwardly extending circumferential flange 54 at its inner end. The box parts 10 and 12 are preferably provided with circular 85 openings of a size to snugly receive the tube therethrough when the openings are in registry and the tube is brought adjacent its closed end 53 with any desired number of circumferential depressions or grooves 54 and 55, the height of the tubular portion 52 being such that when the tube is associated with the box parts by being passed through registering openings aforementioned, the depressions or grooves 54 and 55 will project beyond the outer surface of the 90 box body 10 and in Fig. 8 of the drawing, I show a form of spring lock 57 for locking this fastener 50 in position. This spring lock comprises preferably a circular piece 95 of spring metal slitted radially as shown at 58 so as to provide the tongues 59 which are bent up at their free ends, so that when this member 57 is forced over the outer end or the head of the tube 52, the lips 59 will 100 be flexed outwardly until when, they reach one of the grooves or depressions 54, 55, they will tend to resume their normal positions and position themselves in one or the other of the grooves 54 or 55, depending 105 upon the thickness of the material of which the box parts are made. By using a plurality of grooves displaced longitudinally of the member 50, provision is made for variation in the thickness of the material or 110 in the number of layers employed.

The fastener of the type as shown in Fig. 8 is open to the possibility of manipulation and for this purpose I show in Figs. 9 and 10 another form of fastener 57', in 115 which, in addition to all the other elements 58' and 59' present in the fastener Fig. 8, there is provided a cover member 60 which

is imperforate except for the opening 61 of a size to permit the head 53 of the fastener 50 to pass therethrough.

In Figs. 11 to 15 of the drawing, I show 5 a modified form of box, and in connection with which I may employ a modified form of fastener, and upon viewing Fig. 11 of the drawing, it will be observed that the tray and cover portions 60 and 61 of the 10 box are each formed from a flat sheet of material diagonally creased at the corners so as to permit the corner portions to fold over as shown at 62 and 63, thus forming the three superposed layers at each corner 15 and over which some means must, in practice be provided for retaining these superposed layers in their superposed position and the box parts in their set up position and in accordance with my invention, the means 20 which hold these box parts in their set up position also serve to lock the box parts together against disassociation without detection.

Upon viewing Figs. 11 and 12 of the 25 drawing, it will be observed that the blank of the box parts are provided with a number of slots so that when the box parts are set up, the tray 60 will have the superposed layers at the corners each provided with a 30 vertically elongated slot so arranged as to have the slots at each corner register and form one continuous slot through the superposed layers and for retaining these layers superposed I employ the fastener shown in 35 detail on the right of Fig. 15 of the drawing, this fastener 70 differing from the fastener 20 of Fig. 5 of the drawing in that the side edges of the legs 23 and 24 and of the widened parts 26 and 27 of the neck are 40 provided with the one way teeth 71. The locking element 72 (see Fig. 14) differs from the corresponding element 34 of Fig. 3 in that the slots 73 and 74 are arcuately formed so as to provide not only the bent 45 lips 75 and 76 which correspond to the corresponding lips 37 and 38 of Fig. 3 but also the bent up lips 77 and 78 positioned transversely of the first mentioned lips 75 and 76, the purpose of which will 50 shortly be pointed out.

When this locking member 72 is forced over the two legs 23' and 24' of the embodiment shown on the right hand of Fig. 14, not only will the lips 75 and 76 coat with the 55 diverging outer surfaces of these legs, and with the shoulders 40" and 41" exactly as the corresponding elements cooperate in Fig. 2, but the transversely extending lips 77 and 78 will cooperate similarly with the teeth 71 60 so as to provide for a locking association of the two at any predetermined point to which the two may have been moved.

On the left in Fig. 15 I show a modified embodiment of the locking member of Fig. 65 14 in which the locking member 72' is pro-

vided with the cover member 45" corresponding to and functioning similar to the cover member 45' in the embodiment of Fig. 5 and also provided with the opening or slot 46'.

In the practice of my invention illustrated in Figs. 11 to 15 inclusive, I first insert the fastener 70 on the right of Fig. 15 of the drawing through the registering openings in the superposed layers at each corner of the tray body 60 and then turn these fasteners to a horizontal position, the relative dimensions of the parts being as described in connection with the embodiment of Fig. 1 so that when turned to its horizontal position as shown at the lowermost corner in the tray of Fig. 11, the fastener 70 will be secured in position.

Upon viewing the cover member 61 of Fig. 11, it will be observed that the registering 85 slots at each corner of this box member are horizontal so that assuming the tray to have been filled with merchandise which it is desired to have received therein, and the cover member positioned thereon, the fastener 70 90 already associated with the tray 60 as described can be similarly passed through these horizontal slots and again given a turn at right angles thereto so as to preliminarily 95 lock the cover member 61 to the tray member 60. By now associating with the fastener 70 the locking members 72 of Fig. 14 or the locking member 72' of Fig. 15, the cover box member will be secured in position absolutely 100 against separation.

Having thus described my invention and illustrated its use, what I claim as new and desire to secure by Letters Patent is:

1. In combination with a box part comprising superposed portions, of means for holding said superposed portions in associated relation, said means comprising an element adapted to be passed through the superposed layers and when rotated with reference thereto, to hold said layers against disassociation, and means for locking said member against removal, said means comprising an abutment on said element and an abutment member to be irremovably associated with said abutment.

2. In a device of the character described, in combination, a box construction comprising box parts, one of which has superposed portions, and means for holding the superposed portions in superposed relation and associating together the box parts against disassociation, said means comprising a stud member adapted to be passed through the box part having superposed portions to hold said superposed portions against disassociation when the member is rotated and then adapted to be passed through the other box part to hold the latter in associated relation to said first box part, said means comprising a relatively flat member having a nar-

- rowed intermediate neck portion and a separate element applicable over said stud member to lock the latter against removal.
3. A box construction comprising a body having a slot in a wall thereof, a closure designed to telescope the body and provided with a slot which registers with said body slot at an angle thereto, a rotatable stud having a wedge-shaped head which is constructed to pass through each slot when it is aligned therewith but not otherwise, and a locking member having resilient deflectable portions engageable in an irremovable man-
- ner over said head and being larger than said registering slots; whereby rotation of 15 the stud after passage of the head through the body slot will preliminarily associate the stud with the body, whereby said head may by such rotation be brought into proper position for passage through the closure 20 slot, and whereby application of the locking member will thereupon firmly and irremovably secure said closure to said body.

In witness whereof, I have signed this specification this 1st day of July, 1925.

MARCUS B. BEHRMAN.
